UNITED STATES PATENT OFFICE

ERNEST R. STANDFUSS, OF MILWAUKEE, WISCONSIN, ASSIGNOR TO HARNISCHFEGER CORPORATION, OF MILWAUKEE, WISCONSIN, A CORPORATION OF WISCONSIN

SKIMMER SCOOP

Application filed December 9, 1929. Serial No. 412,650.

This invention relates to an improvement in skimmer scoops employed for tearing up old pavements, for grading and for similar purposes.

Skimmer scoops, as widely employed, comprises a boom supported at one end on the revolving platform of the excavator for raising and lowering movement under the influence of a power operated hoisting tackle. In operative position the boom is horizontally disposed and the skimmer bucket, which is supported for movement longitudinally of and along the boom is pulled outwardly by means of a digging line connected to a digging drum on the platform and extended out and around the guide or digging sheave at the outer end of the boom and back to the bucket. The boom is usually made up of longitudinal channels or angles which are held in spaced relation by a suitable latticing or cross bracing. To support the bucket on the boom, rollers carried by the bucket sides engage exposed longitudinal flanges or tracks provided along the upper and lower sides of the boom. In digging old paving, particularly asphalt paving, slabs of the asphalt curl up in the body of the bucket and are forced up through the open top of the bucket and against the underside of the boom and against the lower exposed tracks on which the rollers bear with the result that the rollers are frequently jammed and the cross bracing or latticing of the boom is bent or otherwise injured.

One of the principal objects of the present invention is to provide a skimmer scoop which so handles and controls the material excavated and particularly slabs of asphalt or the like as to cause them to be deflected into the body of the bucket and prevent them from striking or damaging the boom or its cross bracing or jamming or binding the rollers which support the bucket for its longitudinal travel.

Another object of the invention is to provide a skimmer scoop having these advantages and capacities and which is of simple and durable construction, reliable and effective in operation and easy and comparatively inexpensive to manufacture.

Other objects and advantages reside in certain novel features of the construction, arrangement and combination of parts, which will be hereinafter more fully described and particularly pointed out in the appended claim, reference being had to the accompanying drawing, forming the subject matter of this specification and in which:

Figure 1 is a view in side elevation showing a skimmer scoop embodying the present invention;

Figure 2 is a view of the bucket in top plan with the adjacent portion of the boom broken away and shown in horizontal cross section for the sake of illustration;

Figure 3 is a view in vertical section taken on line 3-3 of Figure 1.

Referring to the drawing, and more particularly to Figure 1, the numeral 1 designates the revolving platform of an excavator supported in accordance with the usual practice of a truck 2 which has the usual self-laying tracks or endless flexible treads 3.

A boom designated generally at 4 is provided and consists of spaced side channels 5 interconnected in any appropriate manner as by means of cross braces or latticing 6. The rearward end of the boom 4 is angled slightly with respect to the major portion thereof as indicated at 4' and is pivotally supported as at 7 on the revolving platform. The boom is also reinforced and strengthened by a truss 8 which overlies the boom and is interconnected therewith in the manner shown in Figure 1. For raising and lowering the boom, a power operating hoisting tackle 10 is provided and coacts with and exerts its lift upon a sheave 11 rotatably supported on the truss 8.

As clearly shown in Figure 3 the outwardly directed flanges 12 and 13 of the side channels 5 of the boom, are provided with wear strips 14 on their inner or confronting faces, these wear strips providing tracks for the rollers of the skimmer bucket designated generally at 15, as will be hereinafter more fully described.

The skimmer bucket 15 includes a body 16 having the usual sides and back and a drop bottom 17 pivotally supported at its lower

end on the side of the body 16 as indicated at 17'. The drop bottom 17 carries excavating teeth designated generally at 18.

For releasably securing the drop bottom 17 in closed position a latch mechanism designated generally at 20 is provided and is carried at the back of the bucket. This latch mechanism may be of any suitable construction, as for example of the type shown in the Patent 1,725,858 granted August 27, 1929, to Joseph Esters and Johannes S. Huber, or a modification thereof. As the latch mechanism per se forms no part of the invention it will not be described in detail.

15 A top designated generally at 22 is provided for the bucket and may consist of suitable casting ribbed and webbed, as illustrated in Figures 2 and 3, to strengthen it and also cut out to lighten the structure of the same.

20 However, this top is sufficiently continuous to deflect into the body of the bucket slabs of asphalt or other paving or other material excavated and also to prevent the slabs and the like from striking or injuring the boom

25 or jamming the rollers. The underside of the casting constituting the top 22 is preferably smooth and the ribs and webs occur entirely on the upper side. As will be understood from Figure 3, the top 22 is located

30 within the bucket body and is riveted, welded, or otherwise suitably secured to the sides and backs of the body 16 thereof. Integral with the top 22 is a pair of side frames or brackets 24 which project upwardly from the

35 top and which in the assembly are located along the outside of the channels 5 of the boom. Each of these brackets 24 supports a pair of upper rollers 25 and a pair of lower rollers 26, the rollers having their pintles or pins 27 supported on the brackets 24 and being freely rotatable. The arrangement of the rollers 25 and 26 is such that the rollers 25 engage beneath the wear strips 14 of the upper flanges 12 while the lower rollers 26

40 ride on the wear strips 14 of the lower flanges 13. As the rollers operate within or between the flanges of the side channels 5 of the boom and coact with the inner or confronting portions thereof, they are protected to a large 45 extent by the boom structure. Further, the top of the bucket precludes the material being excavated from being forced up into the region of the rollers and thus protects the rollers against binding as well as the boom

50 against injury.

Digging movement is imparted to the bucket by means of a digging line 30 connected as at 31 to the top of the bucket, extending around a digging sheave 32 at the outer 55 end of the boom, and back over a guide sheave 33 rotatably supported by suitable brackets on the boom to a digging drum 34 mounted on the revolving platform 1 and driven in any suitable manner by the power plant of the machine.

In operation the boom is positioned, as shown in Figure 1, for grading or tearing up old pavements or for other purposes, and at such time, the bucket 20 is pulled out along the boom by winding up the digging line 30. Due to the provision of the top this operation may be carried out speedily and the bucket may be loaded to its full capacity without danger of injury to the boom and without any danger whatsoever of jamming or binding the rollers. When the bucket has been loaded the boom is usually elevated under the influence of a hoisting tackle 10 and the platform 1 is swung to bring the bucket over the wagon or the other point of discharge and the latch 20 is then tripped whereupon the drop bottom 17 swings about its pivot 17' and the contents of the bucket are discharged. The bucket is returned to its starting position under the action of gravity by paying out on the digging line 30 with the boom inclined so that the weight of the bucket causes it to ride back down along the boom until its back strikes the cushion bumper 40.

The invention claimed is:

A shovel of the skimmer type comprising a boom including side channels and cross bracing between the channels for holding them in spaced relation, said channels having outwardly directed flanges having their confronting portions adapted to provide upper and lower tracks, a skimmer bucket having a top for deflecting excavating material in the body of the bucket, brackets connected to the top of the bucket and projecting upwardly from the top thereof and disposed alongside of the channels of the boom, and upper and lower rollers carried by said brackets and disposed in between the flanges of the channels and engaged with the upper and lower tracks thereof respectively, the rollers engaged with one track being spaced from and out of engagement with the other track.

In witness whereof, I hereto affix my signature.

ERNEST R. STANDFUSS.
